DUPLICATING DEVICE

Harvey J. Reardon, Chicago, Ill.

Application July 14, 1936, Serial No. 90,551

4 Claims. (Cl. 242—55)

This invention relates to a duplicating device. It is an object of this invention to provide an improved duplicating device which is relatively simple and inexpensive in construction and efficient in use.

Another object of the present invention is to provide a new and improved duplicating device of the type which embodies a supporting frame, a roller arranged adjacent each end of the said supporting frame, a gelatin sheet or pad windable alternately onto and off from the said rollers, and means for manually operating said rollers.

An additional object of the present invention is to provide a new and improved device for operating the said rollers.

Another object of the present invention is to provide a novel device for latching the said rollers against retrograde or reverse movement so as to hold the gelatin band or sheet in a preselected position.

A further object of the present invention is to provide a novel and simple device for latching the said rollers in position of use and against accidental or unintentional displacement therefrom.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a preferred form of the new duplicating device;

Fig. 2 is a top plan view of the same, showing a part of the top of the same broken away so as to show the interior thereof;

Fig. 3 is a sectional view, on line 3—3 in Fig. 2, showing the new latching device, embodied in the present invention, for latching the rollers against unintentional or accidental removal from their position of use;

Fig. 4 is a central or longitudinal vertical sectional view, on line 4—4 in Fig. 2;

Fig. 5 is a transverse vertical sectional view, on line 5—5 in Fig. 4;

Fig. 6 is a vertical sectional view on line 6—6 in Fig. 5 showing a preferred form of the ratchet mechanism associated with each of the rollers and the hand knobs for preventing retrograde or reverse movement of the same; and

Fig. 7 is a sectional view showing a modified form of the roller and ratchet mechanism.

A preferred form of the new duplicating device

is shown in Figs. 1 to 6 inclusive of the drawings, is therein generally indicated at 10, and comprises a supporting frame 11 which includes side walls 12 and 13 and a base or bottom wall 14.

Arranged adjacent one end of the supporting frame 11 is a roller 15 and this roller 15 has an end portion or trunnion 16 which is rotatably journaled in a bearing 17 which, in turn, is attached to the side wall 13 of the supporting frame 11 (Fig. 5), this end portion or trunnion 16 having a latching device 31 associated therewith and which latching device will be described in detail hereinafter. At its other end the roller 15 is provided with a key portion 18, which is substantially rectangular in cross section (Fig. 6), and this key portion 18 of the roller 15 is adapted to be inserted into a correspondingly shaped recess or socket 19 which is formed in a short or stub shaft 20, this stub shaft 20 being rotatably journaled in the side wall 12 and having a hand knob or handle 21 attached thereto.

Fixedly mounted on, that is, attached to, the stub shaft 20 is a ratchet 22 and this ratchet 22 is enclosed within a housing 23 (Fig. 6) which is removably mounted on the side wall 12 of the supporting frame 11 in any suitable manner. This ratchet 22 forms a part of a latching device, which is generally indicated at 50, (Fig. 6) and this latching device 50 includes a latch dog 25, the inner end portion 24 of this latch dog 25 being engageable with the teeth of the ratchet 22. This latch dog 25 is pivotally mounted, between its ends, as at 26, upon the side wall 12, and has a handle portion 27 which projects exteriorly of the housing 23 through a slot 28 which is formed in the latter.

The duplicating device 10 also includes a second roller 29 (Fig. 2) which is similar to the roller 15 and is arranged at the opposite end of the supporting frame 11 from the roller 15. Attached to the roller 29, at one end thereof, is a knob or handle 30. One end portion or trunnion 38 of this roller 29 is rotatably journaled in the side wall 13 of the roller 15 (Fig. 5) and associated with the other end portion of the roller 29 is a latching device, which is generally indicated at 49, and which is exactly like the latching device 50 which is shown in Fig. 6 (as being associated with the roller 15 and which has been described hereinbefore), and hence the same need not again be described herein since these parts are duplicates.

Windable alternately onto and off from the rollers 15 and 29 is a gelatin sheet or pad 31

and this gelatin sheet or pad 31 is movable over and across a horizontally extending table or bed 32 which is formed as a part of the supporting frame 11 at the top of the latter.

5 A clamping bail or gripper 33 is pivotally mounted on the supporting frame 11, as at 34, by means of arms 35, and this clamping bail or gripper 33, when in use, serves to bear down upon one end portion of the paper disposed upon the 10 gelatin sheet or pad 31 so as to hold the same in position of use.

The present invention includes the provision of a novel device for latching the rollers 15 and 29 against unintentional or accidental removal 15 from their position of use, and one of these latching devices is shown in detail in Fig. 3, the same being generally indicated therein at 36 and being associated with the roller 29 at one end thereof, an exactly similar latching device 37 being associated with the roller 15 at one end of the latter. However, since these latching devices 36 and 37 are duplicates only one of the same is shown in the drawings and will be described in detail herein, the same being the latching device 36 which is 25 associated with the roller 29.

The latching device 36 includes a latch keeper plate 39 which is attached, as at 40, to the side wall 13 of the supporting frame 11, on the inner side of the said side wall, and formed in this keeper plate 39 is an arcuate slot 41. This slot 41 has a relatively wide throat or inlet 42 and at its inner end the slot 42 is narrowed to a relatively restricted portion 43 which is made just large enough to receive and accommodate the end portion or trunnion 38 of the roller 29. The slot 41 also has an enlarged portion or step 44 which is located just forwardly of, and below, the inner end or restricted portion 43 of the slot 41, for a reason which will be explained presently.

40 The new latching device 36 also includes a latch member 45, which is pivotally mounted between its ends, as at 46, upon the side wall 13 of the supporting frame 12, this latch member 45 having a counterbalanced handle portion 47 at its outer end and having a relatively narrow inner end portion or arm 48 which projects into and works in the slot 41.

Operation

50 In the use of the preferred form of the new duplicating device, which is shown in Figs. 1 to 6, inclusive, the gelatin pad or sheet 31 is arranged upon the device in the manner shown, with its end portions attached to the rollers 15 and 29 in any suitable manner; it being understood, in this connection, that the end portions of gelatin sheets or pads, such as 31, are customarily attached to canvas or other fabric strips and the end portions of the latter are attached to or wound onto the rollers. Accordingly, the body or bulk of the pad 31 may be wound onto one of the rollers, thus, for example, the roller 15, with a portion of the pad extending horizontally over the table 32, it being understood that the gelatin pad 31 may have a plurality of different sets of copy or printed matter written or inscribed thereon in duplicating ink, so that at the start of the operation the first copy to be reproduced may be that which is inscribed onto the 65 end portion of the pad 31 which extends over the horizontal table 32. Thus it will be seen that a plurality of different copies may be reproduced by successively laying sheets of paper or the like on the horizontal portion of the gelatin pad 31 whereon they may be clamped by means

of the clamping bail or gripper 33. Accordingly, as and when it is desired to bring the other sets of copy or inscriptions on the pad 31 into duplicating position, this may be accomplished by turning the hand knob or handle 30 (counterclockwise, as seen in Fig. 1), thereby winding the gelatin pad 31 off from the roller 15 and onto the roller 29.

When the hand knob 30 is rotated, to wind the gelatin pad 31 off from the roller 15 and onto the roller 29, this rotation of the hand knob 30 is transmitted, by way of a key and slot connection, exactly like that shown at 18-19 in Fig. 6, from a stub shaft, (not shown, but which is exactly like the stub shaft 20) to the roller 29, and during this operation the teeth of the ratchet (corresponding to the ratchet 22) of the latching device 49 ride (counterclockwise, Fig. 6) over the end portion of the latch dog (corresponding to the latch dog 25) of the same, it being noted, in this connection, that the end portion of the said latch dog of the latching device 49 is normally urged, by the counterbalanced outer end portion or handle thereof (corresponding to the handle 27) into engagement with the teeth of the ratchet 25 so as to prevent retrograde movement of the latter and the shaft 29 (clockwise, Fig. 6).

Assuming, in the foregoing example, that the gelatin pad or sheet 31 has been wound off from the roller 15 onto the roller 29 (except for the fabric end portions or attaching strips which are arranged at the ends of the pad) and that it is desired to reverse this procedure, and to wind the pad 31 back onto the roller 15; the operator of the device may then accomplish this by grasping the counterbalanced outer end or handle portion 27 of the latch dog 25 of the latching device 50 and pivoting the same (clockwise, Fig. 6) so as to move the inner end portion 24 thereof out of latching engagement with the teeth of the ratchet 22 of the latching device 50, and, while thus holding the latch dog 27 out of engagement with the teeth of the ratchet 22, the operator may, by turning the hand knob 21 (clockwise, Fig. 1) wind the gelatin sheet or pad 31 off from the roller 29 and onto the roller 15. Thus the present invention provides a device for readily and easily unwinding the gelatin pad or sheet 31 off from one roller and onto the other; and the present invention also provides a novel device for latching the rollers 15 and 29 and the gelatin pad 31 in a fixed position and against retrograde or reverse movement when the desired portion of the gelatin pad has been moved into, and latched in, duplicating position.

The exactly similar latching devices 36 and 37 (and one of which is shown in detail in Fig. 3) are designed for the purpose of latching the rollers 29 and 15, respectively, in position of use and against unintentional or accidental displacement therefrom, and likewise for the purpose of enabling the operator of the device conveniently and quickly to remove the rollers as and when desired, for the purpose of replacing the gelatin sheet 31 or for any other reason. Thus, for example, when it is desired to insert the roller 29 into position of use, this may be accomplished by inserting the key portion (similar to the key portion 18, Fig. 6) into the corresponding slot which is provided therefor in the stub shaft on which the hand knob 30 is mounted, (see Fig. 6), whereupon the operator may insert the other end portion or trunnion 38 of the roller 29 through the mouth 42 of the slot 41 and into the restricted or inner end portion 43 of the same, 75

it being noted that during this operation the said trunnion or end portion 38 of the roller 29 will engage the inner end portion or arm 48 of the latch member 45 and will thereby pivot the latter, at 46, (clockwise, Fig. 3). During this operation the inner end portion or arm 48 of the latch member 45 will pivot downwardly into engagement with the notched or lower step portion 44 of the latch keeper plate 39, thus allowing the trunnion or end portion 38 of the roller 29 to 10 pass into the narrow or restricted inner end portion 43 of the slot 41. Accordingly, when the operator releases the latch member 45, the counterbalanced outer end portion 47 thereof will pivot 15 the same, by gravity, at 46, (counterclockwise, Fig. 3) into the position in which the same is shown in Fig. 3; and when the inner end portion or arm 48 of the latch member 45 is disposed in this position it prevents the trunnion or end portion 38 of the roller 29 from accidentally or unintentionally moving out of the slot 41, since with 20 the latch member 45 disposed as in Fig. 3 any lateral movement of the roller 29 will cause the trunnion or end portion 38 of the same to engage 25 the inner end portion 48 of the latch member 45 and thereby jam the latter against the wall 51 of the slot 41. It will, therefore, be seen that in order to remove the roller 29 from its position of use the operator must first manually grasp the 30 outer end portion or handle 47 of the latch member 45 and thereby pivot the same, at 46 (clockwise, Fig. 3), thus moving the inner end portion 48 of the latch member 45 downwardly into engagement with the lower edge portion or step 44 of the latch keeper plate 39, thus allowing the end portion or trunnion 38 of the roller 29 to be moved out through the slot 41 and thereby permitting the roller 29 to be removed from its mountings or position of use, it being understood, 40 in this connection that the latching device 37, which is associated with the roller 15, is similar to the latching device 36, both in construction and in operation, and that the operations of inserting the roller 15 into its mountings and re- 45 moving the same therefrom are similar to those hereinbefore described in connection with the roller 29 and the latching device 36.

It will be seen, therefore, that the latching devices 36 and 37 provide simple and convenient 50 mechanisms for latching the rollers 29 and 15, respectively, in position of use in their mountings and against unintentional or accidental removal therefrom.

A modified form of one feature of the present 55 invention is shown in Fig. 7, and in this form of the invention the end or key portions 18 of the rollers 15 (and 29), which are embodied in the form of the invention shown in Figs. 1 to 6, inclusive, and which are substantially rectangular 60 in cross-section (Fig. 6), are replaced by a pair of pins or lugs 52 which are mounted on, and project from one end of, the roller 53, these being pins or lugs 52 being preferably cylindrical in shape, although other forms or shapes of the 65 same may be employed; these pins or lugs 52 being receivable in correspondingly shaped recesses or sockets (not shown) but which may be provided therefor in the stub shaft 54, which corresponds to this stub shaft 20 in the pre- 70 ferred form of the invention which is shown in Figs. 1 to 6, inclusive, this stub shaft 54 having a hand knob 55 mounted thereon which corresponds to the knobs 20 and 21. Otherwise, that is, except as above distinguished, being similar in 75 construction and operation to the preferred form

of the invention which is shown in Figs. 1 to 6, inclusive.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of 10 the appended claims.

Having thus described my invention, what I claim as new and desire to protect by Letters Patent is:

1. In a duplicating device, a supporting frame including spaced vertically extending side walls and a horizontally extending table or bed arranged between the said side walls and adjacent the top of the latter, a roller rotatably mounted upon the said supporting frame adjacent each end thereof and extending between the said side walls, a gelatin duplicating pad or sheet extending over said table and windable alternately onto and off from the said rollers, means for operating each of said rollers including a stub shaft rotatably journaled in one of the said side walls of said supporting frame and having a socket formed therein, each of said rollers including an end portion or trunnion receivable in the corresponding one of said sockets, means for preventing retrograde or reverse movement of each of said rollers, said second and last-named means including a ratchet mounted on each of the said stub shafts, a latch dog pivotally mounted between its ends on the said one of said side walls and adjacent the corresponding one of said ratchets, each of said latch dogs including an inner end portion engageable with the teeth of the corresponding one of said ratchets, each of said latch dogs having a counterbalanced outer end portion providing a handle normally urging the said inner end portion of the same, by gravity, into engagement with the corresponding one of said ratchets, and means for latching each of the said rollers in position of use and against unintentional or accidental displacement therefrom, each of said last-named means including a latch plate attached to the other one of said side walls and having a slot or groove formed therein for the reception of the said end portion or trunnion of the corresponding one of said rollers, and a latch member pivotally mounted between its ends on the said other one of said side walls and having an inner end portion adapted to project across and close the corresponding one of said grooves, each of said second-named latch members having a counterbalanced outer end portion or handle urging the said inner end portion of the same, by gravity, into position to close the corresponding one of said grooves so as to prevent the withdrawal of the said end portion or trunnion of the corresponding roller therethrough.
2. In a duplicating device, a supporting frame including spaced, vertically extending side walls and horizontally extending table or bed arranged between the said side walls and adjacent the top of the latter, a roller rotatably mounted upon the said supporting frame adjacent one end thereof and extending between said side walls, a gelatin duplicating pad or sheet extending over said table and windable alternately onto and off from said roller, means for operating said roller including a stub shaft rotatably journaled in one of the said side walls of said supporting frame and hav-

- ing a socket formed therein, said roller including an end portion or trunnion receivable in the said socket, means for preventing retrograde or reverse movement of said roller, said second-named 5 and last-named means including a ratchet mounted on the said stub shaft, a latch dog pivotally mounted between its ends on the said one of said side walls and adjacent the said ratchet, said latch dog including an inner end portion engageable with the teeth of said ratchet, said latch dog having a counterbalanced outer end portion providing a handle normally urging the said inner end portion of the same, by gravity, into engagement with the said ratchet, and means for latching 10 15 20 25 30 35 40 the said roller in position of use and against unintentional or accidental displacement therefrom, said last-named latching means including a latch plate attached to the other one of said side walls and having a slot or groove formed therein for the reception of the said end portion or trunnion, a latch member pivotally mounted at its ends on the said other one of said side walls and having an inner end portion adapted to project across and close the said groove, said second-named latch member having a counterbalanced outer end portion or handle urging the said inner end portion of the same, by gravity, into position to close the said groove so as to prevent the withdrawal of the said end portion or trunnion therethrough.
3. In a duplicating machine, a supporting frame including spaced vertically extending side walls, a roller rotatably mounted upon the said supporting frame, and between the said side walls, for moving a gelatin sheet or pad relative to and across said supporting frame, said roller having an end portion or trunnion journaled in one of said side walls, and means for preventing unintentional or accidental displacement of said roller from position of use, said means including a latch keeper plate attached to one of said side walls and having a slot or groove formed therein for the reception of the said end portion or trunnion of the corresponding one of said rollers, and a latch member pivotally mounted between its ends on the said one of said side walls and having an end portion normally projecting into the corresponding one of said slots or grooves so as to close the latter, each of said latch members including a counterbalanced outer end portion or handle normally urging the said inner end portion of the said latch member, by gravity, into position to close the said groove or slot so as to prevent the withdrawal of the said end portion or trunnion therethrough.

HARVEY J. REARDON. 40
